UNITED STATES PATENT OFFICE.

CHARLES H. EVANS, OF JACKSON, MICHIGAN, ASSIGNOR TO THE FAHNEHJELM INCANDESCENT GAS LIGHT COMPANY, OF CHICAGO, ILLINOIS.

GAS-STOVE.

SPECIFICATION forming part of Letters Patent No. 448,579, dated March 17, 1891.

Application filed August 20, 1890. Serial No. 362,467. (No model.)

To all whom it may concern:

Be it known that I, CHARLES H. EVANS, a citizen of the United States, residing at Jackson, in the county of Jackson and State of Michigan, have invented certain new and useful Improvements in Gas-Stoves; and I do hereby declare the following to be a full, clear, and exact description of the invention, such as will enable others skilled in the art to 10 which it appertains to make and use the same.

My invention relates especially to that class of gas-stoves in which fuel-gas, or what is known as "water-gas," is burned.

15 The object of my invention is to provide a gas-stove in which the same burner or burners will serve to heat both a broiler and an oven or a cake-baker, whereby the waste heat from the broiling, roasting, or toasting chamber is utilized for baking. I accomplish this 20 object by providing a foraminated reflecting-plate, preferably above the burners, which thus serves not only to throw the heat toward the articles to be broiled or roasted in the broiling-chamber, but also allows the products of combustion to escape and pass under and around an oven or into and through a chamber above which is located a smooth planished or polished stove-top for baking 25 griddle-cakes and the like.

It is also the object of my invention to provide means whereby the gas-burners may be arranged within a broiling or baking chamber of the stove, and at the same time a sufficient circulation of air will be afforded to obtain a complete combustion of the gas, and especially of the carbon oxide contained therein. This is especially important, inasmuch as gas-stoves of the usual construction do not 35 communicate with chimneys; but all of their products of combustion and fully or partially consumed gases pass directly into the room or other inclosure in which such gas is located. Under such circumstances it is extremely im- 40 portant to insure a complete combustion of the carbonic oxide contained in the fuel-gas, inasmuch as the accumulation of that gas in a room may prove dangerous to life. I have attained this object by providing, preferably,

45 the top of the broiling-chamber with a foraminated plate, whose perforations are conical

and downwardly flaring in shape. This downwardly-flaring arrangement of the perforations greatly accelerates the draft and causes the air to pass to the burners, situated below 55 such foraminated plate, in sufficient quantity to insure a complete combustion of the fuel-gas, and I have devised such further details and combination of parts as will be herein-after pointed out and covered in the claims. 60

I will now proceed to give a detailed description of my invention, reference being had to the accompanying drawings, in which—

Figure 1 represents a vertical section of a stove embodying my invention; Fig. 2, a 65 sectional plan of the same; Fig. 3, vertical section taken on a plane at right angles to that of Fig. 1. Figs. 4 and 5 represent sectional views, taken on planes at right angles to each other, of a modified form of stove embodying my invention. Fig. 6 shows an enlarged view in section of a portion of the conically-perforated plate, and Fig. 7 a detail view of the union for connecting the detachable burner-frame with the permanent gas- 70 pipe.

The same letters of reference designate the same parts in all the views.

The stove shown in Figs. 1 to 3 of the drawings consists of a rectangular casing or frame 80 A, having the walls a' , a' a^2 and a top B, upon which the cooking-vessels are placed, and which is provided with the ordinary pot-holes b, below which are placed the burners b'. Within the frame A is fixed the oven, forming a closed chamber, between which and the casing A are arranged flues for the circulation of the products of combustion for heating the oven, which products finally escape through the opening j. Below the oven is 85 arranged another chamber D, preferably a broiling-oven, and which is arranged similarly to the oven except as to the features now to be described.

The matter so far described is old and well 95 known. It is in the features now to be described that my invention relates.

In the upper part of the broiling-oven D are located the burners h, and above them is arranged a foraminated reflecting-plate J, 100 having the perforations j', which are preferably of conical shape and flaring downward,

as best shown in Fig. 6. By this arrangement of the foraminated plate I am enabled not only to throw sufficient heat downward into the broiling-chamber, but also to utilize 5 the waste heat by carrying the products of combustion through the perforations and upward around the oven C. By the conical shape of the perforations I am enabled, moreover, to produce a far greater draft of air 10 through the same, the air being sucked into them with a much greater force than if the perforations were cylindrical in shape. I am thus enabled to produce the requisite circulation of air to or around the burners to insure a 15 complete combustion of the fuel-gas employed.

The burner-frame II consists of a main conduit G, from which run a number of parallel tubes h, closed at their ends and having perforations h', preferably at their sides. This 20 burner-frame II, it will be seen, may be readily slipped into the stove-casing, which is provided with perforations at the proper point for the insertion of these tubes, as also the broiling-oven D. When the burner-tubes h 25 are inserted into the stove to the full extent, their ends preferably rest upon a ledge i, attached to the interior of the broiler opposite the perforations in the stove-casing above referred to. The tubes h are preferably screwed 30 into the main conduit G, and the latter is connected to the permanent gas-pipe e by a union k, as best shown in Figs. 2 and 7.

When it is desired to remove the burner-frame II from the stove, all that is necessary 35 is to uncouple the pipe e and the main conduit G by turning the union k, when the entire frame may be withdrawn from the stove for the purposes of cleaning or repair, the gas-pipe e having been shut off by turning 40 the cock f.

In Figs. 4 and 5 I have shown a modification of a stove embodying my invention, and wherein the oven C has been entirely omitted, and the broiling-oven L may be here 45 utilized as a baking-oven, the ledges which are shown serving to support shelves when required for such purposes. I have also omitted the pot-lids, but have provided perforations N in the sides of the chamber M, adjacent to the broiler L and above the foraminated plate J, for the escape of the products 50 of combustion. The top of this last-described stove or broiler is covered with a smooth polished plate m, of cast-iron or other suitable

material, upon which griddle-cakes or the like may be baked and the waste heat of the products of combustion passing through the chamber M from the broiler utilized. I thus produce a combined broiler or toaster and cake-baker heated by one and the same burner or burners. 60

I have shown the foraminated plate, oven, or chamber M and burners h as located above the broiling-chamber L; but it is evident that their location might be modified in various 65 ways. All that is necessary is that the supplemental chamber to be heated by the waste heat be adjacent to the broiler and that the foraminated plate be located between the two and adjacent to the burners, so as to reflect 70 their heat into the broiler. Still I prefer the construction as shown. It is also apparent that the devices herein described and shown may be modified in many details without departing from the nature of my invention, and 75 I therefore do not desire to limit myself to the exact details shown and described; but

What I claim, and desire to secure by Letters Patent, is—

1. In a gas-stove, the combination, with a 80 broiling-oven and burners located within the same, of a chamber adjacent to the broiling-oven and a foraminated reflecting-plate adjacent to the burners and between the broiler and the adjacent chamber and extending entirely across the broiler, substantially as and for the purposes set forth.

2. In a gas-stove, the combination of a burner or burners with a partition having conical perforations flaring toward the burner 90 or burners, said partition being arranged over the burners and extending entirely across the interior of the stove, substantially as and for the purposes set forth.

3. In a gas-stove, the combination of a 95 broiling-oven and burners located within the same with a foraminated upper wall located above the burners, extending entirely across the broiling-oven and beneath the heating-chamber above and having conical downward-flaring perforations, substantially as 100 described.

In testimony whereof I affix my signature in presence of two witnesses.

CHARLES H. EVANS.
